CATAMENIAL SAC

Isaac W. Robertson, Los Angeles, Calif.

Application January 10, 1939, Serial No. 250,181

3 Claims. (Cl. 128—285)

This invention relates to catamenial devices.

An object of the invention is to provide a device of the character described which will effectively retain catamenial discharge and which by being fitted into the vagina obviates the use of bulky uncomfortable pads or the like.

Another object of the invention is to provide in open-ended hollow rubber articles improved means for providing a distended or enlarged portion on said article.

Another object of the invention is to provide a catamenial sac adapted effectively to fit within the vagina with the opening of the sac in fluid-sealing relation around the cervix of the uterus, means being provided for modifying the sac to fit vaginas of various sizes.

Another object of the invention is to provide in a catamenial discharge sac of the character described means for preventing the walls of the sac from sticking together to interfere with the efficiency thereof and for retaining such discharge in the sac without spilling the same as the sac is being removed from the vagina.

These and other objects will be manifest from the following brief description and the accompanying drawing.

Of the accompanying drawing:

Figure 1 is a side elevation, partly broken away and in section, of a catamenial sac embodying the invention before insertion of the retaining ring and absorbent pad.

Figure 2 is a plan view, partly broken away and in section, of a retaining ring for the sac.

Figure 3 is a view similar to Figure 1 of the sac with the retaining ring and absorbent pad inserted therein.

Figure 4 is a longitudinal anatomical cross-section through a uterus and vagina illustrating the improved catamenial sac inserted in the vagina and fitted about the cervix for use.

Referring to Figures 1 and 2, the numeral 10 designates a catamenial sac preferably of thin, flexible, impervious material such as rubber latex, having an enlarged portion 11 at the open end. A suitable bead 12, preferably of smaller diameter than the enlarged portion of the sac, may be provided to reinforce the opening 13 in the sac.

For retaining the mouth 13 of the sac in fluid-sealing relation around the cervix 14 (Figure 4), a ring 15 preferably of coiled wire 16 covered with a protective coating of rubber 17 may be provided. Ring 15 readily may be inserted inside the sac 10 at the enlarged end thereof, as shown in Figure 3. These rings

may be supplied in various sizes to fit the cervix of the uterus as required without necessarily changing the size of the sac, as best shown in chain-dotted lines. The sac may have straight sides adjacent the mouth thereof and yet produce the result shown in Figure 3, the bulge 11 serving as a guide to simplify proper positioning of the ring at the mouth of the sac.

A wick or pad 18 of suitable size may be inserted in the sac 10 to prevent the walls thereof from sticking together when the sac is in use (see Figure 4), wick 18 preferably being of fluid absorbing material adapted to absorb the catamenial discharge to enable ready removal of the sac without spilling the contents. It is to be understood, however, that other absorbent material, such as pulp or clay preparations, may be used in place of wick 18.

It will be seen that since the diameter of bead ring 12 of sac 10 preferably is smaller than the diameter of retaining ring 15, there is provided a flanged portion 11^a comprising spaced annular portions of the wall of the sac extending angularly outwardly thereof in parallelism.

For use for the described purposes of the invention, the assembled device, shown in Figure 3, with a piece of moisture absorbent material 18 in the sac 10, is readily retained in a vagina by yieldingly engaging the ring 15 between the posterior fornix and the symphysis pubis, whereby the ring will be in fluid-sealing engagement with the vaginal wall around the cervix of the uterus. Due to the flexibility of ring 15 and the yielding nature of the vaginal wall the ring will readily adapt itself to the shape of said wall without applying a material degree of pressure thereto. The outer flexible annular wall of flange 11^a provides additional fluid-sealing action against the wall of the vagina. Ring 15, by being interchangeable with other rings of varying diameters, greatly facilitates original fitting of the sac 10 to suit the size of the vagina of the user. Thus the improved catamenial device provides effective means for collecting the menstrual flow with little or no discomfort to the wearer, and without unsightly bulges which usually exist when other types of catamenial devices are used.

Modifications of the invention may be resorted to without departing from the spirit thereof or the scope of the appended claims.

For example, it has been found that the ring 15 may be applied to the outside of the sac so as to distend a portion of the wall thereof

turned inwardly around the ring, the result being substantially the same as shown in Figure 3, except that the relative positions of the spaced annular portions of the wall forming the flange 11^a are reversed. The invention is not limited to use in catamenial devices. In a similar manner the rings 15 may be utilized to provide distended or enlarged portions in other hollow open-ended articles such as rubber gloves.

What is claimed is:

1. A catamenial or like device of the character described comprising a sac of impervious, elastic material, said sac being provided with an annular enlarged portion adjacent the open end thereof, and a separate retaining ring removably and replaceably received in said enlargement, the diameter of said ring being substantially greater than the diameter of said enlarged portion to distend said enlarged portion outwardly and thereby provide a flanged portion around the mouth of the sac, the inherent elasticity of said sac retaining said ring in place therein, said sac and ring assembly being adapted to be retained within a vagina by engaging said ring between the posterior fornix and the symphysis pubis to provide a fluid seal with the wall of the vagina around the cervix of the uterus.

2. A catamenial or like device of the character described comprising a sac of thin, impervious, elastic material, the wall of said sac being provided with an enlarged annular portion at the mouth thereof, and a separate ring of relatively greater diameter than said enlarged portion, said ring being retained in said enlarged portion by distending the wall thereof, said distended wall forming a flexible flanged portion at the mouth of the sac, said sac and ring assembly being adapted to be retained within a vagina by engaging said ring between the posterior fornix and the symphysis pubis of the vagina to retain the mouth of the sac in sealed relation with the wall of the vagina around the cervix of the uterus.
3. In an article of the character described the combination of a hollow open-ended sac of flexible, elastic material, said sac being provided with an annular enlarged portion adjacent said open end, and a separate retaining ring of relatively greater diameter than the wall of said enlarged portion whereby the ring is adapted to be removably retained within the enlargement by distending the wall thereof outwardly.

ISAAC W. ROBERTSON.
